(57) **CLAIM**

The ornamental design for an alarm clock, as shown and described.

DESCRIPTION

FIG. 1 is a front, top and right side perspective view of an alarm clock showing our new design;

FIG. 2 is a front side elevational view of the alarm clock of FIG. 1;

FIG. 3 is a rear side elevational view of the alarm clock of FIG. 1;

FIG. 4 is a top plan view of the alarm clock of FIG. 1;

FIG. 5 is a bottom plan view of the alarm clock of FIG. 1;

FIG. 6 is a right side elevational view of the alarm clock of FIG. 1; and,

FIG. 7 is a left side elevational view of the alarm clock of FIG. 1.

The broken lines of FIGS. 1-7 are for the purpose of illustrating structure of the alarm clock that form no part of the claimed design and that are unclaimed subject matter.
